(57) **CLAIM**

The ornamental design for a modular sofa, as shown and described.

DESCRIPTION

FIG. 1 is a top, front and left side perspective view of the modular A of a modular sofa, which are removable arms; FIG. 2 is a bottom, rear and right side perspective view of FIG. 1;

FIG. 3 is a front elevational view of FIG. 1;

FIG. 4 is a rear elevational view of FIG. 1;

FIG. 5 is a left side view of FIG. 1;

FIG. 6 is a right side view of FIG. 1;

FIG. 7 is a top plan view of FIG. 1;

FIG. 8 is a bottom plan view of FIG. 1;

FIG. 9 is a top, front and left side perspective view of the modular B of the modular sofa, which is a chair with backrest;

FIG. 10 is a bottom, rear and right side perspective view of FIG. 9;

FIG. 11 is a front elevational view of FIG. 9;

FIG. 12 is a rear elevational view of FIG. 9;

FIG. 13 is a left side view of FIG. 9;

FIG. 14 is a right side view of FIG. 9;

FIG. 15 is a top plan view of FIG. 9;

FIG. 16 is a bottom plan view of FIG. 9;

FIG. 17 is a top, front and left side perspective view of a first arrangement of the modular sofa, which consists one modular A and one modular B;

FIG. 18 is a bottom, rear and right side perspective view of FIG. 17;

FIG. 19 is a front elevational view of FIG. 17;

FIG. 20 is a rear elevational view of FIG. 17;

FIG. 21 is a left side view of FIG. 17;

FIG. 22 is a right side view of FIG. 17;

FIG. 23 is a top plan view of FIG. 17;

FIG. 24 is a bottom plan view of FIG. 17;

FIG. 25 is a top, front and left side perspective view of a second arrangement of the modular sofa, which consists one modular A and two modular B;

(Continued)

FIG. 26 is a bottom, rear and right side perspective view of FIG. 25;
FIG. 27 is a front elevational view of FIG. 25;
FIG. 28 is a rear elevational view of FIG. 25;
FIG. 29 is a left side view of FIG. 25;
FIG. 30 is a right side view of FIG. 25;
FIG. 31 is a top plan view of FIG. 25;
FIG. 32 is a bottom plan view of FIG. 25;
FIG. 33 is a top, front and left side perspective view of a third arrangement of the modular sofa, which consists one modular A and three modular B;
FIG. 34 is a bottom, rear and right side perspective view of FIG. 33;
FIG. 35 is a front elevational view of FIG. 33;
FIG. 36 is a rear elevational view of FIG. 33;
FIG. 37 is a left side view of FIG. 33;
FIG. 38 is a right side view of FIG. 33;
FIG. 39 is a top plan view of FIG. 33; and,
FIG. 40 is a bottom plan view of FIG. 33.
